UNITED STATES PATENT OFFICE.

OEL E. WARDNER, OF NEW BRITAIN, CONNECTICUT, ASSIGNOR TO TRAUT & HINE MFG. CO., OF NEW BRITAIN, CONNECTICUT, A CORPORATION OF CONNECTICUT.

• BELT-BUCKLE.

1,381,146.

Specification of Letters Patent. Patented June 14, 1921.

Application filed November 22, 1920. Serial No. 425,733.

To all whom it may concern:

Be it known that I, OEL E. WARDNER, a citizen of the United States of America, residing at New Britain, Hartford county, 5 Connecticut, have invented a new and useful Belt-Buckle, of which the following is a specification.

My invention relates to an improved belt buckle, the object being to provide a very 10 simple, inexpensive, and yet effective means for adjustably holding a belt in any position of adjustment.

In the accompanying drawings:

Figure 1 is a perspective view of the in- 15 side of a buckle embodying my invention, and showing the same in operation.

Fig. 2 is a longitudinal horizontal section of the several parts in belt gripping position.

20 Fig. 3 is a similar view of the same parts in the free position.

Fig. 4 is a perspective view of details.

1 represents the main body or front plate of the buckle, which may be in the form of a shield, suitably shaped and ornamented if desired. 2—2 are rearwardly extending flanges at the upper and lower edges of the plate 1. Between these flanges, and preferably near one end of the buckle, are located 25 passages for two pivot pins 3—3. 4 is a cam preferably in the form of a roller from the ends of which the pivot pins 3—3 project, said pins being eccentrically located thereon. When said cam roller stands in the position 30 35 in Fig. 2, its surface will frictionally engage the inner surface of the belt, pinching it tightly against the rear surface of the front plate 1. When the cam 4 is in the position shown in Fig. 3, the belt is free to be adjusted to and fro.

40 5 is a belt attaching or operating lever which is provided with ears 6—6 which are freely pivoted on pins 3—3 at each end of the cam 4. This lever may have any suitable means to which 45 one end of the belt 8 may be secured. 9—9 are guide ears which may be provided on the rear edges of the flanges 2—2 near the opposite end of the buckle from the cam 4. On the cam 4 is a knock off shoulder or pin 10. 50 11 is a shoulder on the lever 5 which may be provided if desired, the function of which is to engage the pin 10 to dislodge the cam from the belt when the lever is swung from

the position indicated in Fig. 2 to that indicated in Fig. 3. By permitting the cam to have a limited amount of rotary movement independently of the lever 5 and vice versa, the buckle is self adaptable to belts of different thickness without interfering with the position of the lever 5 when the belt is in place, that is to say, even though the belt is so thick that the cam 4 engages the same so as to stop turning before the lever 5 is straightened out to the position shown in Fig. 2, the said lever may continue to turn to the straightened out position, the edge of the lever or the shoulder 11 leaving the pin 10. When it is desired to release the belt or readjust it, the lever 5 is swung back until it engages the pin 10, whereupon it will rotate the cam backwardly so as to release the belt, so that the latter may be freely withdrawn, or readjusted as desired. The parts are few in number, simple, and easy to manufacture and assemble. The 75 surface of the cam roller may be grooved, knurled, or otherwise roughened for more effectively engaging the belt than would a smooth surface.

By the arrangement shown, assembly of 80 parts is easily accomplished. The shape of the cam or belt gripping member is such that the mere presence of the belt resting lightly thereon will cause said gripping member to revolve into the belt gripping position when 85 the belt is pulled back. The curvature of the surface of the roller avoids cutting or otherwise injuring the belt.

What I claim is:

In a belt buckle, the combination of a 90 front plate having rearwardly extending flanges along two opposite edges, a belt gripping roller having pivot pins fixed at opposite ends thereof, and located eccentrically thereto, and projecting into openings 95 in said opposite flanges, a belt attaching lever having ears at its opposite edges located between the ends of said roller and the adjacent flanges and freely pivoted on said pivot pins, the belt engaging face of the 100 roller being roughened, a shoulder on the roller arranged to be engaged by the belt attaching lever when the latter is swung back to positively rotate said roller to its belt freeing position.

OEL E. WARDNER.
